(57) **CLAIM**

What is claimed is the ornamental design for a bivalve harvesting platform, as shown and described.

DESCRIPTION

FIG. 1 is an upper perspective view of a bivalve harvesting platform showing the new design;

FIG. 2 is a front view thereof;

FIG. 3 is a rear view thereof;

FIG. 4 is a side view thereof;

FIG. 5 is a side view thereof;

FIG. 6 is a top view thereof; and,

FIG. 7 is a bottom view thereof.

The broken lines showing holes, handles, baskets, and other portions of the bivalve harvesting platform are for the purposes of illustrating the environment of the design or ornamental and form no part of the claimed design. The line breaks shown in FIGS. 1 and 4-7 represent indeterminate length in the handle portion of the claim. The lines and space between the lines form no part of the claimed design.
